UNITED STATES PATENT OFFICE.

GEORGE B. JACKSON, OF GUELPH, ONTARIO, CANADA.

TORPEDO-MAKING MACHINE.

1,308,361.

Specification of Letters Patent. Patented July 1, 1919.

Application filed August 15, 1916. Serial No. 115,063.

To all whom it may concern:

Be it known that I, GEORGE B. JACKSON, a citizen of the United States, residing in Guelph, Province of Ontario, Dominion of Canada, have invented certain Improvements in Torpedo-Making Machines, of which the following is a specification.

The object of my invention is to provide a machine for making torpedoes of substantially the character illustrated in my Patent No. 1,182,767, dated May 9, 1916, and in my pending application for patent filed January 25, 1911, Serial No. 604,685, such torpedoes consisting of a tube of ductile metal containing a charge of detonating material, with the ends of said tube, integral therewith, folded, crimped or otherwise shaped into retaining members whereby the torpedo may be secured to the head of a rail.

Preferably the ends of the tube are longitudinally corrugated or folded in order that a certain amount of strength may be added to the metal comprising the same, and the apparatus constituting the subject of my invention is designed to receive the tubes of ductile metal, prepare the same for the reception of the charge, position the charge therein, fold or crease the ends of the tube, compress said ends after the folds have been placed therein, and then to fold said rail-engaging straps or ends against the central portion of the torpedo, which may then be discharged from the machine in finished form, ready for use.

These and other features of my invention are more fully described hereinafter, reference being had to the accompanying drawings, in which:

Figure 1, is a plan view of one form of torpedo-making machine within the scope of my invention.

Fig. 2, is a side elevation of the same.

Fig. 3, is an end elevation.

Fig. 4, is a sectional view on the line IV—IV, Fig. 1.

Fig. 5, is a sectional elevation illustrating a modified construction within the scope of my invention.

Fig. 6, is a plan view of a portion of the structure shown in Fig. 5.

Fig. 7, is a cross sectional view on the line VII—VII, Fig. 6, and

Figs. 8, 9, 10, 11, 12, 13, 14 and 15, are perspective views illustrating the several

steps performed by the machine in developing a tube of ductile metal into a finished torpedo.

In my improved machine, the ductile tubes *a*, usually of lead and preferably seamless, are placed in a trough 1, shown by broken lines in Fig. 1, and in elevation in Fig. 2, from which they are picked up by pocket members 2 of an endless chain 3, adapted to sprocket wheels 4 and 5 carried by shafts 6 and 7. These shafts are suitably journaled in bearings 6^a and 7^a carried by the frame 8 of the machine, and said shaft 6 may be a driven shaft carrying a ratchet wheel 9, to which motion may be imparted by a pawl 9^a, pivotally mounted on the end of an arm 9^b journaled on the shaft 6. This motion is in the nature of a step-by-step movement; it being necessary to provide intervals of time in operating the chain for certain operations or work upon the torpedo tubes carried thereby. For this purpose, the arm 9^b carrying the pawl is connected by a rod 10 to a bell crank lever 11 pivoted to the frame 8 of the machine at 12, and having its opposite end, preferably provided with a roller 13 in operative engagement with a cam groove 14 formed in a disk 15 carried by a driving shaft 16.

The charges of detonating material to be positioned in the ductile tubes are fed to a suitable pocket 17, from a hopper 18; such pocket being directly adjacent the chain and one end of the tubes carried thereby, so that said charges may be introduced into said tubes directly from said pocket by suitable means, as hereinafter described.

Mounted on top of the frame of the machine and arranged to reciprocate laterally with respect to the chain 3 and the tubes carried thereby are frames 20 and 21; the ends of the same being adapted to guideways at the ends of the frame, and they may be provided with rollers 22 to facilitate their movement. These frames carry suitable members for operation upon the tubes carried by the chain, providing for the insertion of charges to successive tubes and the preparation of the tube ends for their finally folded or crimped condition.

The frames 20 and 21 are provided with racks 25 with which segmental toothed members 26 engage; said members being journaled on shafts 27 mounted in brackets 28

- hung from cross-bars 29 carried by the frame of the machine. These members 26 have arms 30 connected by links 31 to arms 32 on a rock shaft 33 suitably journaled in bearings 34 carried by the frame 8. The rock shaft 33 is provided with an arm 35 in operative engagement with a cam groove 36, in a disk 37 mounted on the driving shaft 16, and said groove may be so constructed that the inward motion of the frames is relatively slower than the outward motion, in order that sufficient time for movement of the chain between said lateral movement of the frames is assured.
- 15 It will be understood, of course, that the tubes are fed successively to the pocket members of the chain and that each tube passes through a series of operations necessary to prepare it for the charge, introduce the charge therein, and then finish the tube and deliver a complete torpedo.

For the description of these several steps, a single tube will be considered; it being understood that for each movement of the frames 20 and 21 all of the operations are being performed upon independent tubes in regular sequence. For clearness of description, I will refer to the operations carried out upon a single tube in its passage through the machine.

At the first stop or station of a tube carried by one of the pockets 2 of the chain 3 and indicated at A, squared forming members 40 carried by said frames 20 and 21 and movable by the latter at right angles to the movement of the chain, are introduced into opposite ends of a tube *a* halted by the chain at said position A. These members 40 are squared and have the effect of changing the shape of the tube at the ends of the same from a relatively cylindrical contour to a rectangular or squared contour, as shown at *b* in Fig. 9, for a purpose hereinafter described. In addition, it is desirable to slightly spread the ends of the tubes for proper coöperation with certain of the forming members, hereinafter described, and for this purpose the members 40 may be provided with short blades 41 set at such position with relation to the tube that when said frames 20 and 21 have been moved the full distance toward the chain with said formers 40 within the tube ends, that said knives will have the effect of slitting for a short distance the squared ends of the tube at the corners of the same, as indicated at *c*, in Fig. 9.

After this operation has been effected, the frames 20 and 21 are retracted, carrying the forming members 40 out of the tubes. The chain 2 is now advanced, bringing the partially formed tube to the second step or station, indicated at B, and the laterally movable frames 21 are again operated toward

the chain, and a pusher member 42 introduces one of the detonating charges from its pocket 17 into the squared end of the tube; the pocket communicating with a delivery channel 43, in the rail 38 in registry with the end of the tube. This pusher 42 is of a length sufficient to bring the detonating charge well within the tube, and such pusher 42 as well as a complementary pusher 42^a at the opposite side of the machine and carried by the frame 21, but having nothing to do with the positioning of the detonating charge, are preferably of such contour and size as to engage the ends of the tube into which they are introduced and change the shape of the same from one in which the vertical dimension is the greatest to one in which the horizontal dimension is the greatest; the reshaped ends being shown at *d*, Fig. 10.

The frames 20 and 21 are again retracted, withdrawing the members 42 and 42^a, and the chain is advanced to the third station or position C. At this point, a plurality of wires 45, suitably carried by the frames 20 and 21 and preferably three in number, with their longitudinal axes in the same horizontal plane, are introduced into the ends of the tube; said wires forming in effect a corrugated mandrel. Simultaneously with the introduction of these wire mandrels, blades 46 and 46^a pivoted at 47 and 47^a to the rails 38 and 38^a are brought in contact with the tube above and below the same; such blades engaging the tube between the wires of the mandrel, and this action will have the effect of crimping or corrugating the walls of the tube at the ends of the same in line with the longitudinal axis of the tube, as shown at *e*, in Fig. 11. In addition, the wire mandrels are of such length as to properly position the charge of detonating material with respect to the tube, in the center of the same. Corrugation or crimping of the tube ends by the blades takes place as the mandrel nears the end of its inward movement, and after such corrugation has taken place, the wire mandrels are withdrawn.

The blades 46 and 46^a which compress the walls of the tube ends between the spaces of the rods or wires forming the corrugated mandrels are more clearly illustrated in Fig. 4; the same being a sectional elevation of the machine on the line IV—IV, Fig. 1. It will be noted in such view that the blades 46 and 46^a are pivotally connected at 47 and 47^a to the rails 38 and 38^a above and below the table over which the chain passes, and are connected at 48 by links or rods 49 with the sliding frames 20 and 21; such links being attached thereto at 50, so that as said frames 20 and 21 are moved toward the chain, the blades will be swung on their pivotal connections simultaneously with the

introduction of the mandrels, around or over the rods of which the walls of the tube ends will be shaped by said blades.

The chain is then moved to bring the tube to the next station D, and laterally movable compressing blades 52 and 52^a, operatively connected to the frames 20 and 21, are brought against the tube ends from opposite sides of the same, which action has the effect of flattening down the corrugated portions formed in said tube ends, as indicated at *f* in Fig. 12. These blades 52 and 52^a are pivoted to the rails 38 and 38^a at 53, and are connected to rods 54 and 54^a at the points 55; said rods being connected at the points 56 to the frames 20 and 21, so that inward movement of said frames will close the blades, and outward movement of the same will open the blades. 20 These blades are provided with flanges 57 and 57^a so that the metal at the ends of the tubes will be held from spreading vertically as it is compressed laterally.

After the frames 20 and 21 have been retracted, opening the blades to the position shown in Fig. 1, the chain is then moved to bring the tube to the next station E, and on its way it passes a roller 60 mounted at the end of an arm or rod 61 carried by and movable with the frame 20, and which is maintained in a relatively fixed position with respect to the chain when the frames are in their retracted position; such roller 60 being so disposed that it will engage one of the folded ends of the loaded torpedo tube and move the same into a position in line with the chain, as shown at *g*, in Fig. 13, and then when the frames 20 and 21 are operated toward the chain, the roller will be carried by its supporting arm 61 and will move the folded end of the torpedo tube against the central portion of the same which has received the charge, as shown at *h*, in Fig. 14.

45 The frames are then retracted, and the chain moved to bring the torpedo to the next station or stop F, where a similar roller 60^a, carried by a rod or arm 61^a has engaged and bent the folded end of the tube in line with the chain, as shown at *g'*, Fig. 14, so that upon the next inward movement of the frames 20 and 21, such end of the tube will be folded over the first end, in the manner described with reference to the same, and as shown at *h'*, Fig. 15.

The chain is again moved after the frames 20 and 21 have been retracted, and upon this movement, or the next movement of the same, the completed torpedo with its folded ends bent back upon the same, as shown in Fig. 15, is discharged from the pocket of the chain.

It will be understood from the foregoing description, detailing the several operations

upon a single tube, that the same operations 65 are being carried out upon similar tubes successively fed to the pockets of the chain, and that each operation referred to takes place in connection with the ends of the tubes at the respective stations or stopping points 70 of the chain.

The pockets 2 of the chain 3 are preferably of the construction illustrated in Figs. 2 and 3, wherein they are represented as having a substantially straight back wall 75 with a curved lip or front wall materially less in height than the back wall; said walls forming a seat for the tubes as they are picked from the trough by the rear wall of the pocket passing through the notch 80 formed in the delivery end of the same.

In some instances, it may be desirable to provide pockets for the tubes in which they may be clamped after the detonating charge has been introduced into the same, and for 85 such purpose I may employ a structure having details such as are illustrated in Figs. 5, 6 and 7.

In Fig. 6, which is a fragmentary view, sufficient, however, to illustrate the modified 90 construction, I have provided a pair of chains 3^a with a series of pockets 2^a, supported at their ends by the same, each pocket having a front wall with a movable central section 62. These sections may be provided 95 with depending portions 63 forming arms for engagement with a cam face 64 formed in the bed-plate so as to be maintained in the open position, ready to receive a tube, until such tube is in place; such depending 100 portions being connected by springs 65 with the links of the preceding pockets, so that when the cam face 64 of the table groove 64^a is passed, the springs will cause the movable portions of the pockets to retract and grip 105 the tubes carried thereby at the center of the same.

In the arrangement illustrated in Figs. 1, 2 and 3, I have shown the use of a single chain for carrying the tube-receiving 110 pockets, while in the modified construction illustrated in Figs. 5, 6 and 7, I employ a pair of chains, suitably guided in grooves 66 of the bed-plate, to which the pockets may be attached by rivets or screws 67.

115 It will be understood, of course, that the means for operating the chain and for operating upon the ends of tubes carried by the special form of chain shown in Figs. 5, 6 and 7 may be identical with those illustrated in Figs. 1, 2, 3 and 4, and that the tubes will be loaded and shaped in the manner illustrated in Figs. 8 to 15, inclusive, to form finished torpedoes.

The ends of the first plungers 40 adapted 125 to enter the torpedo tubes are pointed so that ingress to effect the desired shaping of the tubes, which is to square the ends of the

- same, is easy, and the knives 41 carried by these plungers are set at such position that they just engage the ends of the tubes and slit the walls of the same at the corners thereof. These tubes have their ends shaped substantially rectangularly, with a width less than their height, and the flared end is of material advantage in introducing the charge and the succeeding plungers or tools.
- 10 The charging member 42 has a greater width than height, and the complementary member 42^a on the opposite side of the machine is of the same shape; the ends of said plungers being tapered so that they may readily enter the tube; one of the same pushing the charge in advance thereof, and both plungers acting upon the ends of the tubes to change their shape from a rectangular contour whose height is greater than its width, to a substantially rectangular contour in which the width of the tube ends is greater than their height; preparing them for the reception of the wire mandrels 45 at the next station of the chain.
- 15 The various movable parts of my improved torpedo making machine are actuated from the driving shaft 16, which may be actuated continuously in any usual or approved manner, (not shown).
- 20 I claim:
1. The combination, in a torpedo-making machine, of an endless carrier for receiving open-ended torpedo tubes disposed with their longitudinal axes in horizontal planes, horizontally reciprocating means in line with the longitudinal axes of the tubes for successive action upon both ends of said tubes to shape the same, and means for introducing charges of detonating material within the respective tubes.
2. The combination, in a torpedo-making machine, of an endless carrier for receiving open-ended torpedo tubes disposed with their longitudinal axes in horizontal planes, horizontally reciprocating means in line with the longitudinal axes of said tubes for successive and simultaneous action upon both ends of said tubes to shape the same, and means for introducing charges of detonating material within the respective tubes.
3. The combination, in a torpedo-making machine, of an endless carrier for receiving open-ended torpedo tubes disposed with their longitudinal axes in horizontal planes, horizontally reciprocable means for simultaneously effecting changes in both ends of said tubes to shape the same, means for introducing a charge of detonating material within the tubes, and means for simultaneously crimping both ends of the tubes after the charge is positioned for securing the latter in place.
4. The combination, in a torpedo-making machine, of an endless carrier having pockets for receiving open-ended torpedo tubes

disposed with their longitudinal axes in horizontal planes, means for imparting step-by-step movement to said carrier, reciprocating means for simultaneously imparting a rectangular shape to each end of the respective tubes, and means for introducing charges of detonating material therein.

5. The combination, in a torpedo-making machine, of an endless carrier having pockets for the reception of open-ended torpedo tubes disposed with their longitudinal axes in horizontal planes, means for imparting step - by - step movement to said carrier, means for simultaneously imparting a rectangular shape to each end of the respective tubes, means for introducing rectangular charges of detonating material into the shaped ends of the tubes, and means for positioning the respective charges centrally with respect to the ends of the tubes.

6. The combination, in a torpedo-making machine, of an endless carrier having pockets for receiving open-ended torpedo tubes disposed with their longitudinal axes in horizontal planes, reciprocating means for simultaneously squaring the ends of the tubes, means for introducing charges of detonating material within the tubes and effecting changes in the shape of the tube ends, means for positioning said charges, and means for crimping the ends of the tubes after the charges are positioned.

7. The combination, in a torpedo-making machine, of an endless carrier for moving open - ended torpedo tubes disposed with their longitudinal axes in horizontal planes, horizontally reciprocating means for introducing charges of detonating material within the tubes, means for positioning said charges, means for simultaneously crimping the ends of the tubes, and means for folding the crimped ends against the body of the torpedo.

8. The combination, in a torpedo-making machine, of an endless carrier for moving torpedo tubes, means for squaring the ends of the tubes, means for introducing charges of detonating material into the squared ends of the tubes, means for positioning said charges, means for crimping the ends of the tubes, and means for folding the crimped ends against the body of the torpedo.

9. The combination, in a torpedo-making machine, of an endless carrier, means for moving the same intermittently, pockets mounted on said carrier for receiving open-ended metal tubes disposed with their longitudinal axes in horizontal planes, slidable reciprocating means for introducing charges of detonating material within the respective tubes, and hinged members for crimping or corrugating the tube ends after a charge is in place.

10. The combination, in a torpedo-making machine, of an endless carrier, pockets

- thereon for receiving metal tubes, slidable means for introducing charges of detonating material within said tubes, hinged members for crimping and folding the ends of said tubes, and means for laying said crimped ends against the body of the charge within the torpedo tube.
11. The combination, in a torpedo-making machine, of an endless carrier for open-ended metal torpedo tubes disposed with their longitudinal axes in horizontal planes, and reciprocating means operating in the horizontal plane of the tubes and at right angles to their path of movement for simultaneously effecting changes in the shape of each end of the same.
12. The combination, in a torpedo-making machine, of an endless carrier for torpedo tubes, reciprocating means for simultaneously shaping each end of said tubes, and means carried by said shaping devices for partially slitting portions of the extreme ends of said tubes.
13. The combination, in a torpedo-making machine, of an endless carrier for open-ended metal tubes disposed with their longitudinal axes in horizontal planes, horizontally movable means for introducing charges of detonating material within said tubes, reciprocating means for simultaneously shaping the ends of said tubes before the detonating charges have been introduced, and swinging members for crimping the ends of said tubes after the detonating charges have been introduced and positioned.
14. The combination, in a torpedo-making machine, of an endless carrier for open-ended metal tubes disposed with their longitudinal axes in horizontal planes, means for introducing charges of detonating material within said tubes, and reciprocating and hinged means for simultaneously effecting changes in the shape of each end of said tubes.
15. The combination, in a torpedo-making machine, of an endless carrier for open-ended metal tubes disposed with their longitudinal axes in horizontal planes, means for introducing charges of detonating material within the respective tubes, means for intermittently moving the carrier, and means laterally reciprocable with respect to the endless carrier and in line with the longitudinal axes of the tubes for simultaneous operation upon each end of the respective tubes.
16. The combination, in a torpedo-making machine, of an endless carrier for open-ended metal tubes disposed with their longitudinal axes in horizontal planes, means for introducing charges of detonating material within the respective tubes, means for intermittently moving the carrier, means for simultaneously operating upon the ends of each tube, a pair of frames carrying said tube-end-operating means, and means for effecting simultaneous reciprocation of each of said frames at right angles to the endless carrier.
17. The combination, in a torpedo-making machine, of a supporting frame, an endless chain movable with respect to said supporting frame and adapted to carry open-ended metal tubes to form torpedoes; said tubes being disposed with their longitudinal axes in horizontal planes, a plurality of tools for simultaneous operation upon each end of said tubes to effect changes in the shape of the latter and crimp the same, and means for horizontally reciprocating said tools with respect to each end of the tubes.
18. The combination, in a torpedo-making machine, of a supporting frame, an endless chain movable with respect to said supporting frame, pockets adapted to receive open-ended metal tubes to form torpedoes carried by said chain; said tubes being disposed with their longitudinal axes in horizontal planes, means for intermittently moving said chain, a plurality of tools for simultaneous operation upon each end of said tubes to effect changes in the shape of the same; such operation taking place when the carrier is at rest, horizontally disposed reciprocating carriers for said tools, and means for actuating said carriers.
19. The combination, in a torpedo-making machine, of a supporting frame, an endless chain movable with respect to said supporting frame and adapted to carry open-ended metal tubes to form torpedoes; said tubes being disposed with their longitudinal axes in horizontal planes, a plurality of sets of tools for simultaneous operation upon each end of said tubes to effect changes in the shape of said ends including means for feeding and positioning detonating charges with respect to the tubes, and means for effecting horizontal reciprocation of said tools at each end of the tubes.
20. The combination, in a torpedo-making machine, of a supporting frame, an endless chain movable with respect to said supporting frame and adapted to carry open-ended metal tubes to form torpedoes; said tubes being disposed with their longitudinal axes in horizontal planes, means for intermittently operating said chain, a pair of plungers for preliminarily shaping the ends of the tubes, plungers for feeding detonating charges to the shaped ends of the tubes and reshaping said tube ends, a plurality of sets of tools for simultaneously operating upon both ends of said tubes after the detonating charges are in place, a pair of horizontally disposed reciprocating frames carrying said plungers and tools, and means for operating said frames.
21. The combination, in a torpedo-making machine, of an endless carrier for receiving

torpedo tubes, reciprocating plungers for squaring the end portions of the tubes, and knives carried by said plungers for slitting the walls of the tubes at the ends of the 5 same.

22. The combination, in a torpedo-making machine, of an endless carrier for receiving 10 torpedo tubes, reciprocating plungers for imparting one shape to the end portions of the tubes, and means serving to introduce a charge of detonating material within the tubes and simultaneously change the shape of the end portions of the same.

23. The combination, in a torpedo-making 15 machine, of an endless carrier for receiving torpedo tubes, reciprocating plungers for shaping the end portions of the tubes, means for introducing a charge of detonating material within the tubes, and reciprocating 20 mandrels adapted to enter the end portions of the tubes and position the charge.

24. The combination, in a torpedo-making machine, of an endless carrier for torpedo tubes, means for imparting step - by - step 25 movement to said carrier, means for squaring the end portions of a tube at each stoppage of the chain, means for introducing a charge of detonating material within said tubes, means for positioning said charge, and means for simultaneously grooving the 30 end portions of the tube.

25. The combination, in a torpedo-making machine, of an endless carrier for torpedo tubes, means for imparting step - by - step 35 movement to said carrier, means for squaring the end portions of the tubes, means for introducing squared charges of detonating material within the tubes and simultaneously changing the shape of said end portions, and means for positioning the charges 40 centrally with respect to the tube ends.

26. The combination, in a torpedo-making machine, of an endless carrier for torpedo tubes, means for squaring the ends of the 45 tubes, means for introducing charges of detonating material within the tubes and changing the shape of the tube ends, reciprocating mandrels for positioning said charges, and means coöperating with said 50 mandrels for longitudinally creasing the ends of the tubes.

27. The combination, in a torpedo-making machine, of an endless carrier for moving 55 torpedo tubes, means for introducing charges of detonating material within the tubes, a plurality of parallel wires forming mandrels for positioning said charges, means for longitudinally creasing the ends of the tubes against said mandrels, and means for condensing the creased ends of the tubes.

28. The combination, in a torpedo-making machine, of an endless carrier for moving 60 torpedo tubes, means for shaping the end portions of the tubes to receive charges of detonating material, means for positioning 65

said charges, means for creasing the end portions of the tubes, and means for condensing the creased ends.

29. The combination, in a torpedo-making machine, of an endless carrier for metal 70 tubes, slideable plungers for introducing charges of detonating material within said tubes, hinged members for creasing the ends of said tubes after the charge is in place, and hinged members for flattening the 75 creased ends.

30. The combination, in a torpedo-making machine, of an endless carrier for metal 80 tubes, a reciprocating plunger for introducing charges of detonating material within said tubes, a plurality of sets of hinged members for creasing and flattening the ends of said tubes, and reciprocating rollers for folding said flattened ends against the body 85 of the torpedo.

31. The combination, in a torpedo-making machine, of an endless carrier for torpedo tubes, a pair of reciprocating members for simultaneously shaping each end of said tubes in one form to receive a detonating 90 charge, and a pair of reciprocating members for reshaping the ends of the tubes as said charge is positioned.

32. The combination, in a torpedo-making machine, of an endless carrier for torpedo tubes, oppositely disposed reciprocating plungers for simultaneously shaping each end of said tubes, knives carried by said shaping plungers for partially slitting the extreme ends of said tubes; said tube ends being disposed with their greatest dimension vertically during the slitting operation, and a second set of reciprocating plungers for engaging the tube ends to spread the same after the slitting operation until the greatest dimension of said ends is horizontally disposed, substantially as and for the purpose set forth.

33. The combination, in a torpedo-making machine, of an endless carrier for metal tubes, means for introducing charges of detonating material within said tubes, and sets of reciprocating plungers for simultaneously shaping the ends of said tubes before and after the detonating charges have been introduced; the first set of plungers spreading the extreme ends of the tubes for the ready insertion of the detonating charge and the second set of plungers.

34. The combination, in a torpedo-making machine, of an endless carrier for metal tubes, means for introducing charges of detonating material within said tubes, a set of reciprocating plungers adapted to enter said tubes and a plurality of hinged members coöperating therewith for simultaneously creasing each end of said tubes, and a second set of hinged members for flattening said creased ends.

35. The combination, in a torpedo-mak- 130

- ing machine, of an endless carrier for open-ended metal tubes, said tubes being disposed with their longitudinal axes in horizontal planes and adapted to receive charges 5 of detonating material, means for intermittently moving the carrier, and a plurality of plungers laterally reciprocable in horizontal planes with respect to the endless carrier for simultaneous operation upon 10 both ends of the tubes conveyed by the endless carrier, one of said plungers serving to introduce a charge of detonating material into a tube ahead of its action upon the tube end.
- 15 36. The combination, in a torpedo-making machine, of an endless carrier for open-ended metal tubes, said tubes being disposed with their longitudinal axes in horizontal planes and adapted to receive charges of detonating material, means for intermittently moving the carrier, a plurality of plungers laterally reciprocable in horizontal planes with respect to the endless carrier for simultaneous operation upon both ends of the 20 tubes conveyed by the endless carrier, one of said plungers serving to introduce a charge of detonating material into a tube ahead of its action upon the tube end, a pair of frames carrying said plungers and laterally reciprocable with respect to the endless carrier, and means for operating said frames to retract the plungers faster than they are introduced to the tubes.
- 25 37. The combination, in a torpedo-making machine, of a frame, an endless chain, movable with respect to the same, pockets for receiving metal tubes to form torpedoes carried by said chain, means for intermittently moving said chain, a plurality of tools 30 for operating upon the ends of tubes retained by said pockets when the carrier is at rest, a plurality of sets of hinged members coöoperating with certain of said tools, and reciprocating frames carrying said tools and operating said hinged members.
- 35 38. The combination, in a torpedo-making machine, of a supporting frame, an endless chain movable with respect to the same and carrying open-ended metal tubes to form 40 torpedoes; said tubes being disposed with their longitudinal axes in horizontal planes, means for intermittently moving said chain, a plurality of tools for simultaneous operation upon each end of said tubes, including 45 a plunger for feeding detonating charges thereto, and means for effecting reciprocation of said tools in timed relation with respect to the intermittent movements of the chain.
- 50 60 39. The combination, in a torpedo-making machine, of an endless carrier for open-ended tubes, said tubes being disposed with
- their longitudinal axes in horizontal planes, means for introducing an explosive charge 65 into a tube, and horizontally reciprocable means for reshaping both ends of the tube whereby the walls thereof may be positioned to engage and hold the charge in place.
40. The combination, in a torpedo-making machine, of an endless carrier for open-ended tubes, said tubes being disposed with their longitudinal axes in horizontal planes, means for successively introducing explosive charges into said tubes, and horizontally reciprocable means for simultaneously reshaping 70 both ends of the tubes after the charges are positioned therein to hold the same in place.
41. The combination, in a torpedo-making machine, of a carrier for open-ended metal tubes, said tubes being disposed with their longitudinal axes in horizontal planes, means for introducing an explosive charge 75 into a tube, and horizontally reciprocable means for displacing the metal at both ends of the tube, such displacement effecting changes in the shape of the tube ends and serving to hold said charge in place.
42. The combination, in a torpedo-making machine, of a carrier for open-ended metal tubes, said tubes being disposed with their longitudinal axes in horizontal planes, means for introducing an explosive charge 80 into a tube, and horizontally reciprocable means for simultaneously displacing the metal at both ends of the tube, such displacement effecting changes in the shape 85 of the tube ends and serving to hold said charge in place.
43. The combination, in a torpedo-making machine, of an endless chain for moving tubes through the machine, said tubes being disposed with their longitudinal axes in horizontal planes, means for moving the 90 chain step-by-step, tube-receiving pockets mounted on said chain, and means on both sides of the chain adjacent the ends of the tubes for simultaneous operation upon said 95 ends.
44. The combination, in a torpedo-making machine, of an endless chain for carrying open-ended tubes, said tubes being disposed with their longitudinal axes in horizontal planes, means for moving said chain 100 step-by-step, clamping means in spaced relation mounted on said chain and adapted to receive said open-ended tubes from which the torpedoes are formed, and means on both sides of the chain adjacent the ends of 105 the tubes for simultaneous operation upon said ends.

GEORGE B. JACKSON.
